CLAIM

The ornamental design for a computer, as shown and described.

DESCRIPTION

FIG. 1 is a front, top, left-side perspective view of a computer in accordance with our new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1;

FIG. 7 is a bottom plan view of the computer shown in FIG. 1; and,

FIG. 8 is a front, bottom, right-side perspective view of the computer shown in FIG. 1.

The broken lines immediately adjacent the shaded area represent the bounds of the claimed design while all other broken lines are directed to environment. None of the broken lines form part of the claimed design.
